BATHTUB

Wayne M. Lippert, 2615 N. 75 St., Wauwatosa, Wis.
53215, and William L. Lippert, 398 Wildwood Ridge,
Colgate, Wis. 53017

Original design application Mar. 16, 1971, Ser. No.
125,001. Divided and this application May 30,
1972, Ser. No. 257,994

Term of patent 14 years

Int. Cl. D23—02

U.S. Cl. D23—55

FIG. 1 is a plan view of the bathtub embodying our new design.

FIG. 2 is a sectional view along line 2—2 of FIG. 1.

FIG. 3 is a sectional view along line 3—3 of FIG. 1.

FIG. 4 is a sectional view along line 4—4 of FIG. 1.

FIG. 5 is an enlarged sectional view along line 5—5 of FIG. 1.

FIG. 6 is a sectional view along line 6—6 of FIG. 1.

FIG. 7 is a plan view of a modified form of the bathtub shown in FIG. 1.

FIG. 8 is a sectional view along line 8—8 of FIG. 7.

FIG. 9 is a sectional view along line 9—9 of FIG. 7.

FIG. 10 is a sectional view along line 10—10 of FIG. 7.

FIG. 11 is an enlarged sectional view along line 11—11 of FIG. 7.

FIG. 12 is an enlarged sectional view along line 12—12 of FIG. 7.

This is a division of application Ser. No. 125,001 filed Mar. 16, 1971.

We claim:

The ornamental design for bathtub, as shown.
